United States Patent Office

Des. 215,695
Patented Oct. 28, 1969

215,695

KNOB FOR DOORS, DRAWERS, OR THE LIKE

Morris Loeb, 697 West End Ave.,
New York, N.Y. 10025

Filed Jan. 10, 1969, Ser. No. 15,293

Term of patent 14 years

Int. Cl. D8—03

U.S. Cl. D8—144

FIG. 1.

FIG. 2.

FIG. 1 is a top plan view of the knob according to my invention; and

FIG. 2 is a front elevation of the knob according to my invention.

The dominant features of the design reside in the portions shown in full lines.

I claim:

The ornamental design for a knob for doors, drawers, or the like, substantially as shown and described.
